ELECTRON COUPLED GENERATOR AND
FREQUENCY MULTIPLIERJohn L. Reinartz, Manchester, Conn., assignor to
Radio Corporation of America, a corporation of
Delaware

Application November 14, 1933, Serial No. 697,909

5 Claims. (Cl. 250—36)

The present invention relates to a novel method of and means for producing oscillations of high frequency and to a novel method of and means for increasing the frequency of the oscillations produced if desired.

More in detail, the present invention relates to a novel high frequency generator of the electron type in which the output circuit is coupled to the input circuit by the electron stream only, and to a novel thermionic frequency multiplier and amplifier of the electron coupled type which may be coupled in a novel manner to the novel generator of the present invention to increase the frequency and amplitude of the oscillations generated and supply the same to additional amplifiers or to any load circuit.

The novel features of my invention have been pointed out with particularity in the claims appended hereto.

The invention will be better understood from the following detailed description thereof and therefrom when read in connection with the drawing, in which:

Figure 1 is a wiring diagram of an oscillation generator arranged in accordance with the present invention;

Figure 2 is a circuit arrangement of the oscillation generator of Figure 1 connected with a thermionic amplifier and frequency multiplier arranged in accordance with the present invention; while,

Figure 3 is a detailed illustration of the manner in which certain of the inductances used in the circuit of the present invention may be wound;

Figure 4 is a modified circuit arrangement.

To obviate the necessity for a number of stages when it is desired to double or quadruple the original frequency of a master oscillator, I propose to use any screen grid tube in a novel circuit. The tube, when connected as an oscillator, will function with maximum screening which is necessary at the fundamental frequency or the first or second harmonic of the fundamental frequency. In accordance with the present invention this is accomplished by arranging the circuit so that the filament is at a higher radio frequency potential than the screen grid. The control grid is included as part of the filament radio frequency circuit and is at a higher radio frequency potential than

the filament. The plate is shielded by the screen grid and will operate at the fundamental frequency f that the grid is being operated at or at the second,

$\frac{f}{2}$

or third,

$\frac{f}{3}$

or fourth,

$\frac{f}{4}$

harmonic, as desired, without effect on the operation of the control grid circuit. The value of the coupling condenser 21 determines in part the intensity of the oscillations generated. The condenser 8 aids in balancing the voltage swing across the primary and secondary coils of the transformer 4.

The general connections are shown in Figure 1. In order that the filament K may be operated at a higher potential than the screen grid 2, which is at ground radio frequency potential, the tuning system coil 4 for the control grid filament and filament heating circuit is wound with two wires of such a size that the voltage drop through these wires for the filament current which flows through these wires will not exceed 0.2 volt. In general this wire size need not be larger than number 14 B&S gauge. A convenient method of winding the coil 4 and at the same time allowing it to be self-supporting is to wind the coil the basket weave way. A loop is made at the point where the filament connections are to be made. This tap or loop is at the first one-third of the total winding turns. 21 total turns are required for the 80 meter band, with a tap at the seventh turn, ten total turns for the 40 meter band with a tap at the third turn.

As a master oscillator to drive a tube or tubes as class C amplifiers up to 100 watts input a single screen grid type tube (865) is required when it is desired to double the fundamental frequency only. In this case the output electrode (anode) of the oscillation generator of Figure 1 may be coupled to an amplifier of the class C type in any manner. The amplifier may operate at a fundamental frequency of 80 meters or of 40 meters.

If it is desired to quadruple the frequency from,

say, the 80 meter band to the 20 meter band, I use a second 865 as a screen grid radio frequency amplifier for the triple 20 meter band in order that sufficient excitation may be available for the 5 100 watt class C tube or tubes. Such an arrangement has been shown in Figure 2, in which the (electron coupled) oscillator of Figure 1 is connected by way of a coupling capacity to an additional frequency multiplying and amplifying 10 stage. The input 10 of this stage may be tuned to 40 or 20 meters. If it is desirable to again double the frequency (20 meters) at the second 865 to 10 meters it is best to connect the second 15 865 as an electron coupled oscillator which is excited by the first oscillator and then give the second tube a little additional excitation in addition to that which it gets from the first oscillator (865) by the use of feed-back capacity 21 of the order of 10 to 15 micro-microfarad. The circuit 20 connections for this arrangement are shown in Figure 2. In the second stage the inductances 10 are wound and connected as pointed out in connection with Figure 1. The first stage may be as in Figure 1, except as otherwise indicated.

25 The capacity 21 connected between the control grid and the terminal of one of the windings 4 and the tuning capacity in the first stage may be in the order of 100 micro-microfarads. This capacity provides excitation for the control grid 30 electrode and insures the production of sustained oscillations of a constant frequency which is determined by the inductances connected with said control grid and by the tuning capacity in parallel with said inductance. The second stage of 35 Figure 2 may act as a frequency multiplier and amplifier and in this case is excited or driven by energizing its control grid by oscillations from the output electrode of the first stage. When a higher harmonic of the fundamental frequency 40 80, such as 10 meters, is desired in the output circuit of the second stage, a capacity 21 of less value and variable, connected between the inductances 10 and the control grid of the tube in the last stage, suffices to insure the excitation necessary 45 in addition to the excitation from the first stage which produces the oscillations. This capacity may be adjusted to a value slightly less than that which would be required to insure sustained oscillations were the second stage not excited by a 50 preceding stage. A variable capacity of the order of 5 to 15 micro-microfarads suffices at this point. Of course, if desired, the second stage can be caused to act by itself as an oscillation generator by increasing the value of this capacity. Under 55 the latter circumstances oscillations will produce in the same manner in which they are produced in the first stage.

Any screen grid tube may be used as a crystal controlled tube in the electron stream coupling. 60 When so used the filament is connected at the low radio frequency end of the total coil turns. The crystal is then connected between the control grid and the filament end of the coil, as shown in Figure 4.

65 In all cases the grid leak is connected to the number two wire of the two wire coil; the number one wire is the wire to which the grid condenser is connected and to which the tuning condenser is connected. A by-passing condenser of .01 is connected at the end of the total coil turns to make the two wires a single part of the radio frequency circuit. Such a condenser is also connected to the two coil wires at the beginning of 70 the coil from each wire to the center tap on the

filament transformer. A large by-pass condenser is connected between the center tap and the screen grid. The negative high potential is connected to the center tap and to ground.

Rated voltage is applied to the filament, the 5 screen grid and the plate. The filament voltage is measured at the filament terminals at the socket, after passing through the two coil wires.

When a screen grid tube is used as an electron stream coupled stage greater output can be obtained than when used as a crystal controlled 10 tube, its advantage being in the use as an electron coupled tube. It then acts as a frequency doubler, if so desired, as well as being an efficient 15 buffer. The circuit is simple, no neutralization being required except at the final radio frequency 20 amplifier connected with the output of the circuit of Figure 1 or Figure 2 if it is a triode.

The electron coupled stages operate efficiently 25 and in a stable manner since the only coupling between the input electrodes and associated circuits and output electrodes and associated circuits is by way of the electron stream. Stability of operation is further enhanced by maintaining the screening electrode at low radio frequency 30 potential.

In practice the tuning inductance in the several 35 stages may be of the plug-in type so that the circuits may be readily changed to tune to the desired frequency. Of course, switching means 40 cooperating with taps may be used to change the tune of the circuits.

Having thus described my invention and the operation thereof, what I claim is:

1. Means for producing radio frequency oscillations comprising, a thermionic tube of the screen grid type, a pair of parallel inductances, each inductance having one terminal connected to a different point on a source of heating current, a resistance connecting the other terminal of one of said inductances to the control grid of said tube, a capacitor connecting the free terminal of the other of said inductances to the control grid of said tube, the filament leads of said tube being connected each to its respective one of said inductances and at points thereon such as to include less than half of said inductances in the filament heating circuit, a tuned network in circuit between the anode and the cathode of said tube, and a circuit connected between the screen grid of said tube and the filament of said tube, the last said circuit having an impedance value such that radio frequency currents applied simultaneously to said filament and to said screen grid have a lesser voltage swing on the screen grid than on the filament.

2. An oscillation generator comprising, a thermionic tube having an anode, a cathode, a control grid and a screening grid electrode, a pair of parallel inductances, means for connecting adjacent terminals of said inductances to the control grid of said tube, means for connecting the free terminals of said inductances to different points on a source of heating potential, means maintaining said source of heating current at low radio frequency potential, means for connecting the cathode of said tube to points on said inductances such as to include less than half of said inductances in the cathode circuit whereby the control grid of said tube is at radio frequency potential greater than the radio frequency potential of the cathode of said tube, a load circuit coupled between the anode and cathode of said tube, said load circuit being uncoupled magnetically with respect to said inductances, and means for insur-

ing stable operation of said tube including a connection between the screen grid of said tube and a point on the cathode circuit of radio frequency potential lower than the radio frequency potential of the cathode of said tube.

3. Frequency multiplying means comprising, a thermionic tube having control grid, cathode, screen grid electrode and anode, a circuit for applying a fundamental frequency to be multiplied to said tube comprising a pair of adjacent wound inductances, a capacity connecting an end of one of said inductances to the control grid of said tube, a resistance connecting the end of the other of said inductances to the control grid of said tube, a circuit connecting the free ends of said inductances to different points on a source of cathode heating current maintained at a low radio frequency potential, a circuit connecting the screen grid electrode of said tube to said source of cathode heating current, a circuit connecting points on said inductances to the cathode of said tube whereby the cathode of said tube is maintained at a radio frequency potential intermediate the radio frequency potential of said control grid and said screen grid electrode, a circuit connected between the anode and cathode of said tube, and means for tuning said last named circuit to a harmonic of the fundamental frequency.

30 4. A circuit for energizing the filament and the control grid of a thermionic tube comprising, a pair of parallel inductances wound side by side, a resistance connecting the terminal of one of said inductances to the control grid of said tube, a 35 capacitor connecting the terminal of the other

of said inductances to the control grid of said tube, the filament of said tube being connected to points on said inductances, and a source of filament energizing current connected at different points to the other terminals of said inductances. 5

5. Wave producing means comprising, a thermionic tube having control grid, cathode, screen grid electrode and anode, a circuit comprising a pair of adjacent wound inductances, a capacity connecting an end of one of said inductances to the control grid of said tube, a resistance connecting the end of the other of said inductances to the control grid of said tube, a circuit connecting the free ends of said inductances to different points on a source of cathode heating current, a circuit connecting the screen grid electrode of said tube to said last named circuit, a circuit connecting points on said inductances to the cathode of said tube whereby the cathode of said tube is maintained at a radio frequency potential intermediate the radio frequency potential of said control grid and said screen grid electrode, said capacity being adjustable to feed sufficient excitation energy to said grid to insure the production of sustained oscillations in said circuit of a frequency determined in part by the circuit constants when said tube is to be used as an oscillation generator or to feed less excitation energy to said grid electrode when wave energy is applied to said circuit to be multiplied in frequency, a circuit connected between the anode and cathode of said tube, and means for tuning said last named circuit to the frequency of the oscillations generated or to a harmonic of the applied wave.
